CLAIM

The ornamental design for crimp jaws for pliers, as shown and described.

DESCRIPTION

FIG. 1 is perspective view of a crimp jaw according to the present design;

FIG. 2 is front elevation view thereof;

FIG. 3 is a back elevation view thereof;

FIG. 4 is a right plan view thereof;

FIG. 5 is a left plan view thereof;

FIG. 6 is a top plan view thereof; and,

FIG. 7 is a bottom plan view thereof.

The dashed broken lines in the drawings depict environmental subject matter and form no part of the claimed design.
